DOOR LOCK

James Marsh, Rockford, Ill., assignor of one-half
to Ralph Ladd, Rockford, Ill.

Application February 25, 1939, Serial No. 258,531

2 Claims. (Cl. 292—173)

This invention relates to door locks, and has for the primary object the provision of a device of this character which combines in its construction a latch for a door and a key operated means for locking the latch in door securing position so that the number of parts will be materially reduced over a conventional construction of door lock to permit manufacture at a low cost with less liability of becoming inoperative or broken. 5 and which includes a safety means to prevent the latch from being operated when a key is employed capable of unlocking the lock so that no possibility of the door being opened by an unauthorized person with the key from the outside of 10 the door will be had when the safety means is in use.

With these and other objects in view, the invention consists in certain novel features of construction, combination and arrangement of parts 20 to be hereinafter more fully described and claimed.

For a complete understanding of my invention, reference is to be had to the following description and accompanying drawings, in which

25 Figure 1 is a side elevation illustrating a door lock constructed in accordance with my invention.

Figure 2 is an edge view illustrating the device.

Figure 3 is a side elevation with the cover plate 30 of the lock casing removed.

Figure 4 is a sectional view taken on the line 4—4 of Figure 3.

Figure 5 is a sectional view taken on the line 5—5 of Figure 3.

35 Figure 6 is a perspective view illustrating the latch bolt locking means.

Referring in detail to the drawings, the numeral 5 indicates a lock casing having a conventional face plate 6 provided with openings 7 to receive screws or like fasteners for securing the lock casing in a recess of a door. The lock casing has removable cover walls 8 in which are located aligned keyholes 9 and arcuately curved slots 10 to slidably receive a knob shaft 11 to which knobs 12 are secured. The face plate has a latch bolt opening 13 therein to slidably receive a latch bolt 14.

The latch bolt has the conventional beveled end 15 to engage with a keeper (not shown) and is further provided with a slot 16 in which extends a lug 17 carried by one of the cover plates. A coil spring 18 is arranged in the slot 16 between the lug 17 and one end wall of the slot for the purpose of urging the latch bolt into keeper engaging 55 position.

An arcuately curved arm 19 is journaled on the knob shaft 11 and has its free end pivotally connected to the latch bolt, as shown at 20. A fulcrum lug 21 is formed on one of the cover plates and has a pointed end on which the arcuately curved arm 19 may fulcrum. A downward sliding movement of the knob shaft 11 brings about retraction of the latch bolt against the action of the spring 18. On freeing the knob shaft 11 the spring 18 returns the latch bolt into keeper engaging position. 10

Spaced guide lugs 22 are formed on one of the cover plates of the casing and slidably receive therebetween a locking bolt or member 23 having a cutaway portion to present converging key-engaging faces 24 terminating in a recess 25. The converging faces 24 and the recess 25 are arranged adjacent the key openings 9 so that when a key 26 is inserted in the key openings the bit 27 thereof may engage with the converging faces 20 24 and the recess 25 for imparting a sliding movement to the locking bolt or member 23. 15

A spring-pressed tumbler 28 is pivoted in the lock casing directly under the locking bolt or member 23 and carries a pin 29 engageable with shoulders 30 and 31 formed on the locking bolt or member 23. A leaf-type spring 32 bears against the tumbler for urging the same in a direction to bring the pin 29 thereof in engagement with the locking bolt or member. A portion of the tumbler underlies the recess 25 of the locking bolt or member so as to be engaged by the bit of the key when inserted in the lock casing. 25

To bring about locking of the latch bolt into keeper engaging position, the key is inserted in the keyhole of the lock casing with the bit 27 in engagement with the tumbler and one of the converging faces 24 of the locking bolt or member so that when the key is turned or rotated in one direction pivotal movement is imparted to the tumbler, moving the pin away from the shoulder 31 of the locking bolt and by the bit riding on one of the inclined faces the locking bolt is caused to slide between the guide lugs to occupy a position directly behind the latch bolt so that the latter cannot be retracted. When the locking bolt assumes the latter-named position the pin 29 engages with the shoulders 31 retaining the locking bolt in the position to prevent retraction of the latch bolt, consequently requiring the use of a key and the rotation thereof in a reverse direction to restore the locking bolt or member to its initial position as shown in Figure 3 or out of the path of movement of the latch bolt so that the 40 45 50 55

latter may be retracted by a downward movement of the knob shaft.

- One of the cover plates of the casing is provided with an opening 34 in which a pin 35 may be inserted. When the pin is inserted in the opening 34 it engages the inner end of the latch bolt and consequently prevents the latch bolt from being retracted even though the locking bolt 23 has been returned to its initial position, as shown in Figure 3, through the use of the key. Consequently, the use of the pin 35 in the opening 34 provides a safety means for securing the latch bolt in latching position from the inside of the door so that even if the locking bolt 23 is moved into the position as shown in Figure 3 through the use of a key from the outside of the door, still the door cannot be released due to the fact that the latch bolt is retained in latching position by the pin.
- 20 It is believed that the foregoing description, when taken in connection with the drawings will fully set forth the construction and advantages of my invention to those skilled in the art to which such a device relates, so that further detailed description will not be required.
- 25 What I claim is:

1. A lock comprising a casing having a latch opening, a latch bolt slideable in said opening and provided with a slot, a lug in said casing and ex-

tending into the slot for slidably supporting the latch bolt, a spring engaging said lug and latch bolt for urging the latter into latching position, a knob shaft slidably mounted in the casing for upward and downward movements relative to 5 said latch bolt, an arcuately curved arm fixed at one end on said shaft and having its opposite end pivoted to said latch bolt, and a fixed abutment in said casing at one side of said arm coacting with the latter under downward sliding of said shaft 10 to cause said arm to fulcrum thereon and thereby retract said bolt.

2. A lock comprising a casing having a latch opening, a latch bolt slideable in said opening and provided with a slot, a lug in said casing and ex- 15 tending into the slot for slidably supporting the latch bolt, a spring engaging said lug and latch bolt for urging the latter into latching position, a knob shaft slidably mounted in the casing for upward and downward movement relative to said 20 latch bolt, an arcuately curved arm fixed at one end on said shaft and having its opposite end pivoted to said latch bolt, and a fixed abutment in said casing at one side of said arm coacting with the latter under downward sliding of said 25 shaft to cause said arm to fulcrum thereon with a sliding action and thereby retract said bolt.

JAMES MARSH.
